REMOTE CONTROL APPARATUS

Clyde J. Fitch, Jersey City, N. J., assignor to
 International Business Machines Corporation,
 New York, N. Y., a corporation of New York

Application March 23, 1935, Serial No. 12,574

4 Claims. (Cl. 178—74)

This invention relates to remote control apparatus and is particularly adapted to control various types of units or mechanisms in a distinctive manner upon the reception of successive electrical impulses, the characteristics of which are the same.

More particularly the invention relates to control apparatus comprising a series of relays, and an object of which is to control additional mechanisms upon the reception of successive electrical impulses, having similar characteristics, the first of which causes certain control circuits to be established to render any control mechanism embodied therein energized. This circuit established then remains in this energized condition until a second impulse causes other control circuits to return the energized and controlled mechanism to its normal deenergized or inoperative condition.

This feature may be applied and can be embodied in a considerable variety of constructions, and one of these has been selected for illustrative purposes, since it is believed to exhibit the invention in its most convenient and effective form. It is particularly applicable to tele-printer, case-shift mechanism and when applied in this manner is extremely useful and important in that separate shifting and unshifting control mechanisms are eliminated.

Various other objects and advantages of the invention will be obvious from the following particular description of one form of mechanism embodying the invention or from an inspection of the accompanying drawing; and the invention also constitutes certain new and useful features of construction and combination of parts herein-after set forth and claimed.

In the drawing:

Fig. 1 is a fragmentary sectional elevation illustrating a portion of a tele-printer unit.

Fig. 2 is a schematic circuit diagram embodying the present invention.

Referring now to the drawing in which similar parts are designated by the same numerals in the several views, it is believed that a clear understanding of the invention will be had therefrom when considered in conjunction with the following description.

As mentioned before for illustrative purposes, this invention is shown as embodying a power driven tele-printer or typewriter of the type disclosed in the copending application Ser. No. 677,018, filed June 22, 1933, the construction of which is well known to those in the art, and hence only requires the following brief description.

Referring now to Fig. 1, in the embodiment illustrated in the drawing, well known means are provided for actuating the type bars and case

shift mechanism by power operated devices comprising a power driven roller 10.

A cam 11 is pivoted on one arm of a bell crank lever 12 pivoted in the frame, the other arm of which is operatively connected with one arm of a bell crank lever 13 by means of link 14. The other arm of lever 13 is connected to the type bars (not shown) in a well known manner and fully disclosed in the aforesaid application.

The lever 12 is actuated by the cam 11 when the latter engages the driven roller 10 to be operated thereby. The engagement of the cam 11 with the power roller is controlled automatically by means of the solenoid 18 connected to the key bar 17 by link 19.

The cam 11 is resiliently engaged by a spring-pressed arm 20 which tends to turn it into engagement with the power driven roller or a stop 21 on a lever 22 pivoted on the bell crank 12 and normally arranged in the path of a lug 23 on the cam. When the lever 22 swings to move its stop out of the path of the lug, the arm 20 swings the cam into engagement with the power roller to be actuated thereby to swing the bell crank 12 to actuate its connected mechanism. The lever 22 has an arm 24 which is provided with an offset projection 25 at its end which projects laterally through an opening in the bell crank 12 and engages the bifurcated lower end 26 of an arm 27 of a key lever 17 pivoted on the common rod 28 and linked to the solenoid 18. It is obvious then that energization of solenoid 18 in causing a key lever 17 to be depressed releases the revolubly mounted cam 11 to engage and be actuated by power roller 10 in turn operating bell crank 12 and its attached links to cause the associated mechanism such as the key bars or case shift mechanism to be operated.

One of the links 16 connected to a bell crank 12 is associated with the case shifting mechanism (not shown) well known in the art and a disclosure of which is given in U. S. Patent No. 1,945,097 issued to R. G. Thompson, et al., January 30, 1934, so that further description is not necessary since the case shifting mechanism itself is not claimed as part of this invention. It is understood that the case shift mechanism remains in its operated position so long as the controlling key bar 17 is depressed which is the common practice.

Referring now to Fig. 2, one method of connecting the series of relays is shown, the functions of which may be to control the operation of the key-lever mechanism described hereinbefore, so that, for example, the case shift lever mechanism remains in its shift or operated position upon the reception of the first signal impulse, and to replace the mechanism to its unshift position upon the receipt of a second impulse having the same characteristics.

The signal impulses are impressed upon terminals 31 and 32 to condition the connected relay circuits as follows: The first signal impulse applied to the said terminals causes current to flow from terminal 31 to relay tongue 2—A, normally closed contact 1—A, conductor 33, relay tongue 2—C, normally closed contact 1—C, conductor 34, relay tongue 2—B, normally closed contact 1—B, conductor 35, coil of relay A, conductor 36 to terminal 32, energizing relay A. The contacts 1—A and 3—A of relay A are adjusted so that upon its energization the movable and actuated tongue 2—A closes the connected circuit through contact 3—A before the connected circuit through contact 1—A is broken, so that it is seen that the signal impulse is impressed directly upon contact 3—A through relay tongue 2—A to continue to energize the coil of relay A by the said impulse. Energization of relay A also causes its contact 5—A to be closed permitting a current flow from the positive terminal 37 of battery 30, conductor 39, normally closed contact 5—C, relay tongue 4—C, conductors 40 and 41, relay tongue 4—A, contact 5—A now closed, conductor 42, coil of relay B, conductor 43, solenoid 18, to terminal 38 of battery 30, energizing relay B and key bar solenoid 18.

Energization of relay B establishes a locking circuit through its contact 5—B now closed, from terminal 37, conductor 39, contact 5—C, tongue 4—C, conductors 40 and 44, tongue 4—B, contact 5—B, coil of relay B, conductor 43, solenoid 18 to terminal 38. In this manner relay B remains energized for an indefinite period and in turn maintaining the energization of the solenoid 18 for any desired period after the reception of the signal impulse.

Energization of solenoid 18 in the manner just described causes a key-lever 17 to be depressed to release the cam 11 and then actuated by power roller 10 to rotate the cam a half revolution which causes the bell crank lever 12 to operate its connected mechanism, for example, the case shift mechanism, through the connecting link 16.

The case shift mechanism or any connected mechanism, will remain in this operated position during the period solenoid 18 remains energized. Upon the receipt of the second signal impulse at terminals 31 and 32 the relay circuits are conditioned as follows: Current flows from terminal 31 to relay tongue 2—A, normally closed contact 1—A, conductor 33, tongue 2—C, normally closed contact 1—C, conductor 34, tongue 2—B, contact 3—B now closed, conductor 45, coil of relay C, conductor 46 to terminal 32, energizing relay C. The 1—C and 3—C contacts of relay C are adjusted similarly as the contacts 1—A and 3—A of relay A, in that, the tongue 2—C is adapted to close or engage contact 3—C before breaking or opening the contact 1—C. The purpose of this contact adjustment is to prevent interruption of the signal current impressed thereon when the relay C is energized by the said current.

Energization of relay C causes the normally closed contact 4—C to be opened, which opens the locking circuit from battery 30 for relay B and described hereinbefore, causing the relay B and solenoid 18 to be deenergized. Deenergization of solenoid 18 causes its connected key-lever 17 to be released so as to restore the case shift or other connected mechanism to its nor-

mal or original position. Relay B is restored to its original position as shown in the figure setting up its connected circuits so that when relay C is deenergized another impulse impressed on terminals 31 and 32 the coil of relay can be energized in the manner described. Relay C is deenergized upon the cessation of the second signal impulse, to restore all of the connected circuits to the normal position.

While there has been shown and described and pointed out the fundamental novel features of the invention as applied to a single modification, it will be understood that various omissions and substitutions and changes in the form and details of the device illustrated and in its operation may be made by those skilled in the art without departing from the spirit of the invention. It is the intention therefore to be limited only as indicated by the scope of the following claims.

What is claimed is as follows:

1. In a remotely controlled mechanism, the combination of an operating instrumentality, control means for operating said instrumentality, a plurality of relays, one of which is adapted to be operated by a signal impulse to cause the operation of a second relay, a locking circuit for said second relay established upon its operation so that the said second relay continues to operate the said control means upon cessation of said impulse, and an additional relay operated by another signal impulse to disable the said second relay.

2. Control apparatus of the character described, comprising a plurality of relay devices, a source of signal current, a circuit to apply the signal current to one of said relays, mechanism control means, circuits established under the control of the said relay to operate the said control means upon receipt of the signal impulse, an additional circuit adapted to be connected to said current source under the control of the said relay, and means included in the said additional circuit to disable the control means upon the receipt of a second signal impulse.

3. In a remotely controlled recording mechanism, operating instrumentalities, power operated devices individual to said instrumentalities, a plurality of keys each adapted to cause actuation of one of the power operated devices, means for operating said keys, means activated by a signal impulse, a relay energized upon the activation of said means to operate the key operating means, and a locking circuit for said relay established upon its operation so that the said relay continues to operate key operating means upon cessation of said impulse.

4. In a remotely controlled recording mechanism, operating instrumentalities, power operated devices individual to said instrumentalities, a plurality of keys each adapted to cause actuation of one of the power operated devices, means for operating said keys, a plurality of relays, one of which is adapted to be energized by a signal impulse to operate a second relay, a locking circuit for the said second relay established upon its operation so that the second relay continues to operate the said key operating means upon cessation of said impulse, and an additional relay energized by another signal impulse to disable the said key operating means.
